Andrew Shultz

UNITED STATES PATENT OFFICE

CHARLES G. STEFFEN, OF SOUTH JAMAICA, NEW YORK, ASSIGNOR TO DUGAN BROTHERS INC., OF BROOKLYN, NEW YORK, A CORPORATION OF NEW YORK

MACHINE FOR APPLYING ADHESIVE TO WRAPPERS OF PACKAGES

Application filed November 26, 1930. Serial No. 498,303.

My invention relates to machines for applying adhesive and for fastening wrappers of packages and is particularly adapted for fastening by means of paste or other adhesive the folded wrappers of bread and the like.

An object of my invention is to provide means for applying paste, or other adhesive material to the wrappers of packages and 10 a further object of my invention is to provide means for fastening or sealing packages.

I accomplish these and other objects by my invention a preferred embodiment of which is illustrated in the accompanying drawing, 15 in which

Figure 1 is a plan view of the machine and

Figure 2 is a side view with the paste container shown in section on the line 2-2 in Figure 1.

20 Similar characters of reference refer to similar parts throughout the several views.

My improved machine is particularly adapted for fastening the ends of the wrappers on loaves of bread and the preferred form of the machine illustrated in the drawing is adapted to be used for that purpose.

Referring to the drawing, the machine illustrated comprises an open trough having 25 a bed 1 and side walls 2, 2 upon which are set counterpart paste containers 3.

These paste containers 3 are open and are each provided with a roller 4 freely rotatable with their shafts 5 and are adjustably 35 positioned by means of a cam 6 from which they are suspended by means of an arm 7.

The cams 6 are rotatable by handles 8 keyed on the drafts 9.

The side walls 2 are provided with slots 10 which are carried adjacent the bed 1 to a point approximately in the plane of the open end of the paste container 3 from which point they are continued upwardly as shown at 10¹ at an obtuse angle to the top of the side 45 walls 2.

The rollers 4 which form end closures for the paste containers 3 are spaced from the overhang 11 of the bed 1 a distance sufficient to permit the ends of the wrappers to 50 pass thereunder. The bearing shafts 5 of the

rollers 4 are preferably carried in elongated bearing sockets 12 to permit free movement longitudinally of the paste receptacles.

A conveyor of any desired type may be provided to carry the wrapped packages. 55

The machine being thus assembled, the loaves of bread 14 having wrappers placed thereon in any desired manner are fed to the machine on the bed 1 in the direction of the arrows in Figure 1, with the folded ends 15 of the wrapper lying flat and projecting through the slots 10 and these folded ends 15 of the wrapper are passed under the rollers 4 whereby paste from the paste container 3 is applied to the exposed surface. 60

As the package 14 is moved along the bed 1 the inclined portion 10¹ of the slot will cause the ends 15 of the package to be folded upwardly and the sidewalls 2, 2 of the trough being spaced apart a distance equivalent to 70 the length of the completed package, will cause the folded ends 15, so provided with adhesive material, to be pressed against the package thus completing the sealing of the package, which is then carried away by the 75 conveyor 13.

Having thus described my invention, what I claim is:

1. In a device of the character described the combination of a trough having a bed 80 and slotted side walls, means mounted on the said side walls exteriorly of the trough for applying adhesive material to the end of a flap of a wrapper projecting through said slotted side wall and comprising a container, 85 a roller forming a loose closure for the container, elongated bearing slots in the walls of said container, a shaft in said bearing slots and rotatably carrying said roller, and supporting means for said container comprising a cam, a shaft eccentrically mounted in said cam, a support for said shaft, an arm carried by said cam and secured to said container and key means adapted to rotate the said shaft. 90

2. In a device of the character described, means for applying adhesive material, comprising a container for said material, a roller forming a loose closure for the container, bearing slots in the walls of said container, a 100

shaft in said bearing slots and rotatably carrying said roller, in combination with supporting means for said container comprising a cam, a shaft eccentrically mounted in said cam, a support for said shaft, and an arm carried by said cam and secured to said container.

Signed at New York in the county of New York and State of New York this 20th day of November A. D. 1930.

CHARLES G. STEFFEN.
